UNITED STATES PATENT OFFICE.

SAMUEL W. LOWE, OF PHILADELPHIA, PENNSYLVANIA, ASSIGNOR TO HIMSELF AND WM. F. SCHEIBLE.

PRINTING-PRESS.

Specification of Letters Patent No. 15,428, dated July 29, 1856.

To all whom it may concern:

Be it known that I, SAMUEL W. LOWE, of the city of Philadelphia and State of Pennsylvania, have invented certain Improvements in Printing-Presses; and I do hereby declare that the following is a full, clear, and exact description of the same, reference being had to the accompanying drawing and to the letters of reference marked 10 thereon.

My invention relates to improvements in small portable printing presses, in which a radiating cone shaped roller, is used for giving the required impression, and consists 15 in a means of so adjusting the conical roller as to easily adapt it to the surface of the type from which the impression has to be taken. In connection with the conical roller I also employ a spring tympan, so arranged 20 in respect to the roller, and its center of radiation, that on turning the said roller in the direction of the tympan, the latter will be depressed over the type, and on turning the roller away from the tympan the latter 25 will, by means of its spring be raised and thus allow the paper to be placed readily upon the type.

In order to enable others skilled in the art to make and use my invention I will now 30 proceed to describe its construction and operation.

On reference to the drawing which forms a part of this specification, Figure 1 is a 35 sectional elevation of my improved portable printing press with the conical roller directly over the type; Fig. 2, a ground plan of Fig. 1, and, Fig. 3, an external elevation of the press with the roller removed from the tympan, and in a position at right angles 40 to the same, and the tympan consequently through the action of the spring raised from the type.

The above views (in which the same letters of reference allude to similar parts) 45 are drawn one half the full size of the press.

A is the base plate of the press the shape 50 of which is represented in the plan view Fig. 2. Into the projecting portion *a* of this plate is screwed, or otherwise secured the vertical spindle B, and toward the top of the latter fits accurately, but so as to turn freely the end of the radial lever C, between which and the base plate and surrounding 55 the said vertical spindle intervenes a spiral

spring *e*, the latter having a tendency to keep the end of the radial lever pressed upward against the nuts *f*, *f'*, which are adapted to the screwed portion *h* of the vertical spindle B. The end of the lever C is furnished 60 with an operating handle *c*, and from the underside of the lever project two brackets *i* and *j*, the former serving as a loose bearing for the spindle D, and the latter having an oblong slot through which passes the 65 opposite end of the same spindle; the extreme end of which is screwed, and has a nut *d*, which in conjunction with the collar on the other end, in the projection *i* serves to keep the said spindle always in the same 70 longitudinal position. Near the end of the lever C is a screw *k*, projecting with its point into the slot (already mentioned) of the bracket *j* and bearing against the shaft D; on the latter and between the two brackets *i* and *j* is the roller F which tapers toward the center of the vertical spindle B. This roller is so arranged that on turning 75 it on its center of radiation (that is the shaft B) its surface shall always coincide 80 with that of the type E which is attached to the base plate A in any convenient manner.

G is the tympan frame made of a piece of wire and bent in the form shown in Fig. 2; from this wire project pieces *m*, *m*. These 85 are turned and bent into orifices in the base plate A, thus forming a hinge for the tympan. Across the tympan wires is stretched the blanket H, said blanket being formed of the substances usually employed for similar 90 purposes. Attached to the wire G which composes the tympan frame, at points indicated in Fig. 2, are the ends of the spiral spring *w* which surrounds a protecting ferrule *y* partially inclosing the spiral spring *e*. The object of this spiral spring *w*, in its tendency to raise up the tympan when the latter is not depressed by the action of the roller F will be apparent as the moment the 95 roller is removed from the tympan, the latter will rise by the action of the said spiral spring.

Operation: When the above described apparatus has to be used for printing, the operator in the first instance grasps the handle *c* of the radial lever C, and moves it either to the right or to the left so that it shall be clear of the tympan wire G. The latter immediately, through the spiral spring rises to the position shown in Fig. 100 105 110

3, and allows the printer every opportunity of distributing the ink over the type, and afterward placing the paper on the same, then on drawing the lever C in the direction 5 of the tympan, the roller F will in the first instance depress the same, and afterward passing over the cloth leave the desired impression on the paper.

I would here remark that I am aware 10 that radiating conical rollers have been used for giving impressions on plain surfaces, but the difficulties of using such conical rollers have hitherto been this, that in constant use the central point of radiation 15 springs or yields, and consequently the surface of the conical roller has not the desired effect on the surface of the tympan, as the slightest yielding of the lever consequent upon the weakness of the vertical spindle B 20 must cause a corresponding lightness on the extreme surface of the type E.

By my arrangement of parts the moment the roller F does not perform efficient duty on the outside of the type E it can soon be rectified by the regulating of the screw *k*. 25

I do not desire to claim the employment of a cone shaped roller for giving impressions, well knowing that the same has been employed before. But

What I claim and desire to secure by 30 Letters Patent is,—

1. The adjusting of the conical roller F by means of the screw *k* as herein specified.

2. The radiating lever C with its conical roller F in combination with the tympan 35 and its spring *x* the whole being arranged substantially in the manner and for the purpose herein set forth.

SAM. W. LOWE.
